Term of patent 14 years

(Cl. D34—15)

Fig. 1

Fig. 2

FIGURE 1 is a side perspective view of a hobbyhorse, showing my new design, the other side having substantially the same appearance.

FIGURE 2 is a front elevational view of the hobbyhorse.

The characteristic features of my design comprise the combination of the platform forming the footrest and its supporting rods and the curved frame rising from the supporting rods and forming the open arms and the back support and the mounting of the horse's head.

I claim:

The ornamental design for a hobbyhorse, as shown and described.
